UNITED STATES PATENT OFFICE.

CHARLES HENRI VESSOT AND ALLAN GILMOUR MATHER, OF OTTAWA, ONTARIO,
CANADA.

FLAX-PULLING MACHINE.

1,184,593.

Specification of Letters Patent. Patented May 23, 1916.

Application filed June 5, 1915. Serial No. 32,408.

To all whom it may concern:

Be it known that we, CHARLES HENRI VESSOT and ALLAN GILMOUR MATHER, both subjects of the King of Great Britain, and 5 residents of the city of Ottawa, Province of Ontario, Dominion of Canada, have invented certain new and useful Improvements in Flax-Pulling Machines, of which the following is the specification.

- 10 This invention relates to improvements in flax pulling machines of the type in which the flax is pulled through the medium of contacting inclined pulling belts and the objects of the present invention are to give 15 greater flexibility to the mechanism so that it will adjust itself to varying conditions of the crop and to provide for additional expansion and contraction between the individual pulling belts.
- 20 Further objects are to improve the driving mechanism to reduce the number of belts employed both for pulling and for driving.

Further objects still are to improve the 25 power supply whereby the power may be adjusted to the work required of it.

The invention comprises a plurality of pulling elements movable as a whole to and from each other and each containing a pulling 30 belt adapted to contact and coöperate with a corresponding belt in the next element, means for holding the pulling elements resiliently together and means for supplying power to the pulling belts, all as 35 hereinafter more fully set forth and described in the accompanying specification and drawings.

In the drawings, Figure 1 is a plan view of the machine. Fig. 2 is a detail side view. 40 Fig. 3 is a side view of the pulling element. Fig. 4 is a detail of the rear of the support for the pulling element. Fig. 5 is a detail in plan of one of the pulling elements with the upper casing removed. Fig. 6 is a perspective view of the spring tightening mechanism.

In the drawings like characters of reference indicate corresponding parts in all the figures.

50 Referring to the drawings, A represents the frame of the machine which may be attached to or form part of the frame of an ordinary binder. This frame is supported on wheels B and C and is drawn by a suitable tongue 10.

D represents a transversely extending collecting belt usually found on binders by which the pulled flax plants are collected.

E, E represent the central pulling elements and F, F the outer pulling elements. 60 Each of the central pulling elements is of the construction shown in detail in Figs. 3 and 5 while the outer elements F are of similar construction, but have the belt extending only on one side and forming each 65 in substance just one-half of a complete element. Each element E includes a casing 12 including an upper plate 13 and a lower plate 14.

The pulleys 15, 16, 17 and 18 supporting 70 the flax pulling belt G are mounted between the plates 13 and 14 in any suitable way, the pulleys 16 and 18 having any convenient type of adjustable bearing by which their position may be altered to tighten or loosen 75 the tension on the belt.

In the embodiment illustrated the flax pulling belt is driven from a shaft H which extends transversely beneath all the elements E and F and which has pulleys 20 80 mounted at intervals thereon, around which pulleys the belts G are adapted to extend, being turned downwardly for this purpose over pulleys 21 and 22 mounted in the plate 14.

85 It will be seen that a single belt G extends around all of the pulleys 15, 16, 17, 18, 20, 21 and 22, the course of the belt G being as follows: from the pulley 15 to the pulley 16, then to the pulley 22, around the pulley 22 to the pulley 20, then around the pulley 21 to the pulley 17, around the pulley 17 to the pulley 18, around the pulley 18 to the pulley 15, to the place of beginning. It 90 will be seen that this forms a simple and effective means of drive and at the same time acts as a pulling belt for the flax.

95 The belts and adjacent pulling elements E, E and F, F are adapted to remain in contact, and to assist them in remaining in contact rollers 24 and 25 are provided on opposite sides respectively of the casing 12, the rollers on one side being spring mounted so that they will exert a resilient pressure on the inner side of the belt G.

100 We have shown the pulleys 25 having pins 105 tles 26 slidably mounted in slideable bearing blocks 27, the bearing blocks being connected to rods 28 all of which rods extend through a longitudinally extending bar 29 110

between which and the bearings springs 30 extend. The bar 29 is adjustably connected to the plate 13 by slot and bolt connections 31 whereby its position may be adjusted to 5 vary the tension of the springs.

At the forward part of each pulling element engaging belts I are provided, the engaging belts and adjacent pulling belts diverging from each other. These engaging 10 belts, which may be chains if desired, are mounted on sprockets 40 and 41, the sprockets 41 being connected to and turning with the pulleys 15 and 17. Each of the pulling elements is further provided with a pointed 15 nose 42 adapted to divide the crop. The pulling elements are all supported with freedom of slight lateral movement. The support comprises brackets 43 on the rear end of the pulling elements and slidably mounted 20 on a transversely extending rod 44 secured to the frame A and conveniently supported therefrom by brackets or bearings 45. The forward parts of each element are supported by pivoted arms 46 which are pivoted 25 to brackets 47 by pins 48, the brackets 47 being connected to or forming part of the frame A.

The pulling elements are adapted to be held resiliently against each other as a whole 30 by means of a compression spring 50 bearing against a bracket 51 on the end frame F and the tension of the spring 50 is adapted to be adjusted to suit crop conditions by suitable means. The means we have shown 35 to accomplish this comprises a follower plate 52 extending around the rod 53 which is connected to the bracket 51 and extends through the spring 50. This follower plate has connected to it cords 54 which extend 40 around pulleys 55 mounted in a fixed bracket 56. From the pulleys 55 the cords 54 extend over pulleys 57 and 58 to a hand lever 59 adjacent to the driver's seat 60, the hand lever being adapted to be held in 45 adjusted position by any usual expedient, such as the arcuate rack 61 and corresponding dog, not shown, on the lever. It will be seen that when the lever is adjusted tension on the spring 50 will be varied.

50 Tripping arms J are provided on each of the pulling elements adapted to engage the flax plants and cause them to drop in a substantially horizontal position onto the collecting belt D.

55 The power for driving the pulling belts in place of, as formerly, being derived from the traction wheels is derived from a separate source of power, such as the gasoline engine K which is connected by suitable 60 gearing with the shaft H. The gearing we have illustrated, but which is not material, comprises a sprocket 70 on the shaft H connected by a chain 71 with a sprocket 72 on a countershaft 73 carrying a pinion 74 which meshes with a gear 75 on a counter-

shaft 76 carrying a beveled gear 77 which meshes with a pinion 78 on a countershaft 79 which carries a sprocket 80 connected by a chain 81 with a sprocket 82 on the shaft of the engine K.

In the operation of the invention, the machine by any convenient means of power, such as draft animals, is advanced against the flax crop and the pulling belts operated at a convenient speed. The pulling belts 75 being set at an inclination of gravity to the horizontal will raise the flax plants and pull them in the preferred manner, depositing them on the collecting belt D which will convey them to the binding mechanism, or 80 will discharge them in any place desired. If the crop is particularly thick the speed at which the machine is fed against it may be lessened. In this way a constant speed may be maintained from the engine K. Also 85 when the crop is particularly thick the tension pressing the members E and F together may be lessened.

It will be seen that there are two tensions, that of the pulling elements against each 90 other and that of the belts of the pulling element against each other.

As many changes could be made in the above construction and many apparently widely different embodiments of our invention, within the scope of the claims, constructed without departing from the spirit or scope thereof, it is intended that all matter contained in the accompanying specification and drawings shall be interpreted as 100 illustrative and not in a limiting sense.

What we claim as our invention is:

1. In a flax puller and in combination, a plurality of pulling elements placed side by side containing coöperative contacting pulling belts and being laterally adjustable as a whole relatively to each other.

2. In a flax puller and in combination, a plurality of pulling elements placed side by side containing coöperative contacting pulling belts and being laterally adjustable as a whole relatively to each other, and spring means for holding the pulling elements against each other.

3. In a flax puller and in combination, a plurality of pulling elements each containing pulleys and pulling belts, means for supporting each of the pulling elements with freedom of lateral movement, and spring means pressing the pulling elements laterally against each other.

4. In a flax puller and in combination, a plurality of pulling elements, each containing pulleys and pulling belts, means for supporting each of the pulling elements with freedom of lateral movement, spring means pressing the pulling elements laterally against each other, and means for varying the pressure of said spring means.

5. In a flax puller and in combination, a

plurality of pulling elements, each containing pulleys and pulling belts, means for supporting each of the pulling elements with freedom of lateral movement, spring means 5 pressing the pulling elements laterally against each other, and means for varying the pressure of said spring means, said means including a follower plate, cords connected to the follower plate, pulleys supporting the cords, and means for holding 10 the cords in adjusted position.

6. In a flax puller and in combination, a pulling element having pulleys on opposite sides, a cross shaft extending beneath the 15 same, a pulley on the cross shaft, a single belt extending around the pulleys on both

sides of the pulling element and around the pulley on the shaft.

7. In a flax puller and in combination, a plurality of pulling elements each containing 20 pulling belts, brackets supporting the rear part of said elements, a rod supporting said brackets with freedom of lateral movement and pivoted arms supporting the forward end of said pulling elements.

In witness whereof we have hereunto set our hands in the presence of two witnesses.

CHARLES HENRI VESSOT.

ALLAN GILMOUR MATHER.
